UNITED STATES PATENT OFFICE.

FRANK RUDOLPH SCHMID, OF CARTHAGE, NEW YORK, ASSIGNOR TO
JENNIE L. SCHMID, OF CARTHAGE, NEW YORK.

PIANO.

SPECIFICATION forming part of Letters Patent No. 690,035, dated December 31, 1901.

Application filed February 8, 1901. Serial No. 46,480. (No model.)

To all whom it may concern:

Be it known that I, FRANK RUDOLPH SCHMID, a citizen of the United States, residing at Carthage, in the county of Jefferson 5 and State of New York, have invented certain new and useful Improvements in Pianos; and I do declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to new and useful improvements in pianos, and especially to certain features of construction whereby faults common in pianos having a full iron-plate covering, which covers the whole wrest- 20 plank and which prevents pianos from staying in tune any considerable length of time, are obviated. In my improvements I decrease the size of the iron-plate covering and increase the thickness of the wrest-plank, and 25 by placing the tuning-pins through the thickened part of the wrest-plank I reduce the leverage of the string upon the tuning-pins in a large measure, and by this construction the tuning-pins have a greater hold upon the 30 wrest-plank than in pianos of ordinary construction having a full iron-plate covering. By reducing the pull on the tuning-pins I add correspondingly to the resisting power of the tuning-pins by their being seated in and having a greater hold upon the wrest-plank. 35

The invention relates, further, to certain features whereby I improve upon the tonal quality of the upper register of the piano, giving it a clear, bell-like tone so much 40 sought after, and to accomplish this I arch the treble-bar in my piano-plate, which obviates the necessity of cutting the belly-bridge at the point at which the treble-bar crosses. As the sound-waves follow the long fibers of 45 the wood, by cutting the bridge these waves are necessarily interrupted, and the distribution and flow of the tone over the sounding board would be by such cutting impaired.

The invention relates, further, to certain 50 details of construction, which will be herein-

after more fully described, and then specifically defined in the appended claims, and is clearly illustrated in accompanying drawings, which, with the characters of reference marked thereon, form part of this application, 55 similar characters of reference indicating like parts in the two views, in which—

Figure 1 is a front elevation of the treble end of the piano-works; and Fig. 2 is a sectional view on line 2 2 of Fig. 1 vertically 60 through the piano, parts being shown in elevation.

Reference being had to the details of the drawings by letter, A designates the posts at the upper end of the piano-back, which form 65 the foundation for the wrest-plank. This wrest-plank is made up preferably of several layers (indicated by numerals 1, 2, 3, 4, 5, and 6) and a base portion B of the hardest kind of quarter-sawn rock-maple, which are 70 glued together, so that their grain runs in opposite directions. In these layers, forming the wrest-plank, the pins C are seated.

My invention as so far described differs from the common construction of pianos in 75 the addition of the extra three layers or strips 1, 2, and 3 of wood forming a thickened portion of the wrest-plank, which are located beyond and contiguous to the marginal edge of the iron covering-plate, the lower end 80 of which terminates at 4. The space ordinarily occupied by these three extra sections thickening the wrest-plank is ordinarily occupied by a continuation of the iron covering-plate C. Where this plate covers the entire wrest-plank, apertures are made through the iron plate, with a slight space intervening 85 between the marginal wall of the aperture and the pin, so as to avoid contact of the tuning-pin with the metallic edge, which 90 causes a metallic quality of tone. By shortening the iron covering-plate, having the same terminate at the point D, Fig. 2 of the drawings, and placing the tuning-pins through the extra thickness of the wrest-plank, it will 95 be observed that the leverage on the string is decreased and the hold of the pins upon the wrest-plank correspondingly increased. The top portion of my plate C is cast with a flange F on its lower edge, which flange en- 100

gages under the lower edges of a portion of the strips making up the wrest-plank, and being securely held thereto renders the pulling down of the wrest-plank impossible.

5 E designates the sounding-board of my piano, which is shown as resting at one end upon the lower portion B of the wrest-plank. Adjacent to the lower end of the base portion B of the wrest-plank on which the sounding-board rests is a cut-away portion N, which extends over a large area of the treble end of the piano, thus allowing a larger space underneath the extreme treble end of the instrument.

15 Projecting from the iron covering-plate C is a bridge G, over which the bass-strings of the instrument pass and are held in position thereon by means of pins g. The strings in the treble part of the instrument are held by 20 tuning-pins H, which pass through the wrest-plank, also the iron covering-plate, and the treble-strings (one of which is shown in Fig. 2 of the drawings) are secured to these pins H and in a lower plane than the plane in 25 which the bass-strings are located. Said treble-strings rest upon the bridge C², which is integral with the iron covering-plate opposite the flange portion F thereof, and a pressure-bar K is fastened by screws or other 30 suitable means to the wrest-plank and held securely against the treble-strings at a location between the pins H and the bridge C².

35 L designates a bridge upon which the treble-strings are held by means of the pins L', and L² designates a portion of the bridge which is crossed by the treble-bar M, which is arched. This treble-bar is arched, as at N', at a location where it crosses said portion L², thus avoiding the necessity of cutting the bridge, 40 which would impair the efficiency of the instrument.

45 C³ designates a raised portion of the iron covering-plate on which the treble-strings rest.

45 In Fig. 2 of the drawings the keyboard Q is shown resting upon a shoulder or bracket portion of the treble-bar.

50 R designates one of the treble-hammers, parts being broken away between the keyboard and said striker-head.

55 From the foregoing it will be observed that by reducing the size of the iron covering-plate and thickening the wrest-plank beyond the margin of said plate I provide an extra thickness of the layers of the wrest-plank in which to locate the tuning-pins, which will decrease the leverage on the strings, and the tuning-

pins will have a larger bearing upon the wrest-plank than would be the case if the covering-plate extended to the upper end of the 60 wrest-plank and the pins passed through apertures therein. By cutting away the wrest-plank adjacent to the flanged portion of the covering-plate I provide a large sounding-board space at the treble end of the piano 65 and by the arching of the treble-bar where it crosses the belly-bridge avoid the necessity of cutting same, which would interfere with the flow of the sound-waves which follow the long fiber of the wood. By cutting 70 the bridge the distribution and flow of the tone over the sounding-board is greatly interrupted.

What I claim as new, and desire to secure by Letters Patent, is—

1. In a piano, a covering-plate, a wrest-plank made up of sections having an extra-thickened portion beyond the marginal edge of said covering-plate, the latter terminating against the lower edges of the sections of said thickened portion, a portion of said covering-plate engaging the edges of other sections of the wrest-plank, and serving as an additional support to said wrest-plank, as set forth. 75

2. In a piano, a covering-plate, a wrest-plank having a thickened portion extending beyond the marginal edge of said covering-plate, the latter terminating against the extra-thickened portion of said wrest-plank, the outer face of said thickened portion of the 80 wrest-plank extending beyond the outer face of the covering-plate, a bridge and a flange on said plate said flange bearing against the wrest-plank, as set forth. 85

3. In a piano, a covering-plate, a wrest-plank extending beyond the marginal edge of said plate, a flange F of said plate engaging the said wrest-plank, a portion of said 90 plank having a curved recess, a sounding-board resting on the latter adjacent to said curved recess, and a rib C³ oppositesaid flange, as set forth. 95

4. In a piano, a covering-plate, a wrest-plank having a thickened portion beyond the outer margin of said plate, a flange on said 105 plate engaging the wrest-plank, and a sounding-board resting on a cut-away portion of the wrest-plank, as set forth.

In testimony whereof I hereunto affix my signature in presence of two witnesses.

FRANK RUDOLPH SCHMID.
